(57) **CLAIM**

We claim the ornamental design for a display screen or portion thereof with icon, as shown and described.

DESCRIPTION

FIG. 1 is a front view of a display screen or portion thereof with icon showing our new design; and,

FIG. 2 is another front view, in which the display screen or portion thereof with icon is provided in an alternate embodiment.

The dot-dash broken lines in the figures represent the display screen or portion thereof and form no part of the claimed design.
